UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

THREAD-CONTROLLING MECHANISM FOR SEWING-MACHINES.

1,276,127.

Specification of Letters Patent. Patented Aug. 20, 1918.

Application filed September 15, 1916. Serial No. 120,335.

To all whom it may concern:

Be it known that I, DUDLEY S. SEYMOUR, a citizen of the United States, residing at Oak Park, in the county of Cook, State of Illinois, have invented certain new and useful Improvements in Thread-Controlling Mechanism for Sewing-Machines, of which the following is a description, reference being had to the accompanying drawing and 10 to the figures of reference marked thereon.

The invention relates to new and useful improvements in thread controlling mechanisms for sewing machines, and more particularly to the thread controlling mechanism for needle threads of a multiple needle stitching mechanism, such, for example, as shown in the patent granted to Russel G. Woodward, April 29, 1890, No. 427,026.

Prior to my invention, as shown in the 20 patent referred to above, it had been customary to provide a slack thread controlling device which was actuated by the presser foot as the thickness of the material varied so as to vary the slack supplied to the needle 25 in accordance with the thickness of the material being stitched. This slack thread controlling device operated upon the threads of all the needles.

An object of the present invention is to 30 provide a thread controlling mechanism wherein there is a slack thread controlling device for the thread of each needle which is independently controlled by the thickness of the material adjacent the respective needles.

35 In the drawings:—

Figure 1 is a front view of a sewing machine having my improvements applied thereto, a portion of the cloth plate being 40 broken away to show the looper;

Fig. 2 is an enlarged detail view, partly in front elevation and partly in section, showing the end of the overhanging arm and the thread controlling devices thereon;

45 Fig. 3 is an enlarged detail, in side elevation, of the end of the overhanging arm and the thread controlling devices;

Fig. 4 is a plan view of the end of the overhanging arm and the thread controlling 50 devices attached thereto;

Fig. 5 is a plan view showing a portion of the end of the overhanging arm, the thread controlling levers, and the thread guides carried thereby;

Fig. 6 is a view, similar to Fig. 2, but 55 showing a slightly modified form of the invention;

Fig. 7 is a view, similar to Fig. 3, but 60 showing this modified form of the invention; and

Fig. 8 is a view, similar to Fig. 4, but 65 showing the modified form of the invention.

It is well-known that the thickness of the 70 fabrics being stitched often varies considerably and devices have been provided for giving slack to the needle threads which devices are controlled by the presser foot so that, as the thickness of the fabric increases, more slack is given to the needle threads and as the thickness of the fabric decreases, less slack is given thereto. An example of this 75 mechanism is shown in the Woodward patent above referred to. In this patent, there are two needles, and a single controlling device operates upon both of the needle threads.

The present invention consists primarily 80 in providing a separate and independent controlling device for each of the threads of a multiple needle stitching mechanism, and these controlling devices are separately actuated by the thickness of the material adjacent the respective needles. In one form 85 of the invention the presser foot is divided longitudinally, forming two sections which are mounted so as to yield independently of each other. These sections bear on the fabrics adjacent the respective needles.

When the thickness of material being 90 stitched by one needle increases, the section of the presser foot bearing on this increased thickness will be relatively raised. If the thickness of the fabric at this time adjacent the other needle is not increased, then the 95 section of the presser foot bearing thereon will not be raised. As above noted, there is a separate thread controlling device for each needle. One of these thread controlling devices is connected with one section of the presser foot, and the other is connected with the other section of the presser foot. Therefore, when the thickness of the fabric increases at one needle and not at the other, additional slack thread will 100 be given to the one needle where the thickness has increased. It is obvious that this separate control of the needle threads for 105

the respective needles may be accomplished in other ways, the essential feature being that each thread controlling device will be responsive to the thickness of the material 5 adjacent its respective needle.

Referring more in detail to the drawings:—

I have shown the invention as applied to a sewing machine having a work support 1 10 which is mounted on a bed plate 2. An overhanging arm 3 is carried by the bed plate, and in the free end of the overhanging arm the needle bar 4 reciprocates. This needle bar is provided with two needles 5 and 6. 15 Coöoperating with the needles 5 and 6 beneath the work support is a looper 7 which is mounted on a carrier 8 pivoted to a looper support 9. The looper carrier 8 is oscillated by a link 10 from the needle lever extension 20 11 of the needle lever 12. The needle bar is reciprocated by this needle lever 12 through a link connection 13. Said needle lever is oscillated by an eccentric strap 14 which coöperates with an eccentric on the 25 main shaft 14^a.

The material to be operated upon is held upon the work support by a presser foot 15. This presser foot is carried by a presser bar 16 which is mounted in the overhanging arm 30 3. The presser bar is held normally against the work support by a leaf spring 17 and may be raised by a hand lever 18. The presser bar 16 is also connected to a guide bar 19 which reciprocates in suitable lugs 35 20. These parts are of the usual construction, and further description thereof is not thought necessary.

The presser foot 15 is formed in two sections 21 and 22. The section 21 is rigid 40 with the shank of the presser foot, while the section 22 is yieldingly supported on the shank. The manner of supporting the yielding section will be described in detail hereinafter. The yielding section is forced to 45 toward the work support by a spring 23. The two sections 21 and 22 are formed by dividing the presser foot longitudinally, and these two sections are so located that the needle 5 passes through the yielding section 50 22 of the presser foot, while the needle 6 passes through the rigid section 21.

The thread for the needle 6 is indicated at *n*, while the thread for the needle 5 is indicated at *n'*. The thread *n* passes through 55 the tension 24, and thence through a guide eye 25 formed in a wire attached at 26 to a thread controlling lever 27. This thread controlling lever 27 is mounted on a pivot stud 28 and is formed with a segmental gear 60 29, which meshes with a rack 30 attached to a collar 31, which collar is clamped by a set-screw 32 to the presser bar 16. The needle thread *n'* passes through a tension 33, and thence to a guide eye 34 formed in 65 a wire attached at 35 to a thread con-

trolling lever 36, and thence to a thread guide 42 at the upper end of the needle bar. This thread controlling lever is mounted on the pivot stud 28 and is formed with a segmental rack 37 which meshes with a rack bar 38. The rack bar 38 is rigidly attached to a sleeve 39 which is free to slide on the presser bar 16. An arm 40 is also attached to the sleeve 39, and this arm projects downwardly and is secured to the section 22 of the presser foot. The section 22 of the presser foot is provided with a shank 22^a which fits within a pocket formed in the shank of the fixed foot section 21. The section 22 has bodily movements in a vertical plane only. The lower end of the arm 40 is reduced to form a stem 40^a and a resultant shoulder 40^b. This stem fits in a corresponding vertically disposed opening formed in the shank 22^a, and is fixed thereto by a cross pin 22^b. When the section 22 is up, as shown in the drawings, the shoulder 40^b will be disposed at a point above the offset shank of the section 21 so as to allow section 22 to drop below the section 21. The shoulder 40^b also limits the downward movement of the section 22 relative to the section 21 when the presser bar is raised by the operator. The openings in the offset shank at each end of the cross pin 22^b are merely 90 for the purpose of inserting or withdrawing said cross pin.

From the above description, it will be apparent that, when the section 21 of the foot is raised, the presser bar 16 moving upwardly therewith will lift the rack 30, and this will oscillate the controlling lever 27 so as to move the thread guide 25 downwardly. This downward movement of the thread guide gives up slack to the needle, as the position of this thread guide relative to the tension 24 and the thread guide 42 has been changed. In other words, a downward movement of the thread guide 25 brings it nearer to a straight line between the thread guide 42 and the tension 24 and, of course, this gives slack to the needle thread passing through the guide. Both needle threads *n* and *n'* pass through this guide 42 and then to their respective needles. If the section 22 is not raised at the time the section 21 is raised, then the arm 40 remains as before, the presser bar 16 sliding in the sleeve 39 and, therefore, the guide 34 for the needle thread *n'* does not shift and no additional slack is given to this needle thread. It will thus be seen that, if the thickness of the material increases under the section 21 of the foot, while the thickness of the material under the section 22 remains the same, additional thread will be given to the needle 6 to accommodate this extra thickness of the fabric, without giving up any additional thread to the needle 5 so that the needle loops of the respective 130

needles will both be drawn tight although the thickness of the fabric has varied under one section only. If the thickness of the fabric increases under the section 22, then the 5 reverse operation of the parts occurs, the thread guide 34 moving downwardly to give up slack to the needle 5, while the thread guide 25 maintains its normal position. If the fabric varies under both sections of the 10 presser foot, then both guides will be moved to give slack to the needles.

It will be apparent from the above description that I have provided a thread controlling device for each needle thread which 15 is responsive to the thickness of the fabric being stitched by its respective needle. While I have described the thread controlling levers as controlled by a sectional presser foot, it will be understood that these levers 20 may be otherwise controlled, the essential feature being the separate and individual control of the devices by the varying thicknesses of the materials being stitched by the needles. While I have shown a single 25 looper coöperating with both needles, it will also be understood that other forms of complementary stitch-forming mechanism may be used as the thread controlling devices regulating particularly the needle loops in the 30 stitches being formed.

In Figs. 5 to 7, inclusive, I have shown a slightly modified form of the invention, the stitch forming mechanism and the presser foot mechanism being precisely the same as 35 above described. The thread controlling lever 27 carrying the thread guide 25 is also controlled in precisely the same way by the rack bar 30 carried by the collar 31 which is secured to the presser bar 16. The thread 40 controlling lever 36 carrying the thread guide 34 is controlled in a slightly different manner. This thread controlling lever 36 is formed with a segmental rack 37 which meshes with a rack bar 43. This rack bar 45 is attached to a sleeve 44 in order to slide 45 freely on the presser bar 16. Said sleeve has a downwardly projecting bar 45 which is pivoted at its lower end on a pin 46 attached to a lever 47. This lever 47 is ful- 50 crumed at 48 on a bracket 49 which is attached to the lower end of the guide bar 19 for the presser bar 16. The end of the overhanging arm 3 is formed with an opening for the depending arm 45. The lever 47 is forked at its front end to engage between 55 shoulders 50 and 51 formed on the shank 52 carrying the yielding section 22 of the presser foot. The spring 23 bears on the upper end of this shank. As the section 22 60 is raised, the shank 52 will move upwardly therewith, and this will raise the free end of the lever 47. The lever will move the arm 45, the sleeve 44, and the rack bar 43 upwardly, and this will depress the thread 65 guide 34.

The operation of these parts is precisely the same as those described above, the only difference being the including of the lever between the arm on the sleeve and the shank of the section 22 of the presser foot.

It is obvious that minor changes in the details of construction and the arrangement of parts may be made without departing from the spirit of this invention, as set forth in the appended claims.

Having thus described the invention, what is claimed as new is:—

1. The combination of a work support, stitch-forming mechanism, said stitch forming mechanism including a plurality of 80 needles, a slack thread-controlling device for each needle, and a movable fabric-engaging member adjacent each needle, said slack thread controlling device for each needle being connected to the movable 85 fabric-engaging member adjacent its respective needle.

2. The combination of a work support, a presser foot, stitch-forming mechanism, said stitch-forming mechanism including a plurality of needles, a slack thread controlling device for each needle, said presser foot having an independently movable section for 90 each needle, and devices for connecting the slack thread controlling device for each needle with the corresponding section of the 95 presser foot.

3. The combination of a work support, a presser foot coöperating therewith, said presser foot being divided longitudinally to 100 form two independently movable sections, stitch-forming mechanism including two spaced needles disposed so as to operate upon the material passing under the respective sections of the presser foot, a thread controlling lever for each needle thread, a thread guide carried by each controlling lever, and devices for connecting one of the thread controlling levers to one of the sections of the presser foot, and independent 105 devices for connecting the other thread controlling lever to the other section of the presser foot.

4. The combination of a work support, an overhanging arm, a needle bar, two needles 115 carried by said needle bar, a thread guide at the upper end of the needle bar for the needle threads, tension devices on the overhanging arm for the needle threads, a thread-controlling lever pivoted to the overhanging arm for each needle thread, a thread guide carried by each thread controlling lever, the thread guides on the controlling levers being so disposed relative to the tension devices and the guide on the end of the 120 needle bar whereby movements of the levers will either give or take up slack thread in the respective needle threads, and means controlled by the thicknesses of the fabrics being stitched at the respective needles for 125 130

- varying the position of the thread-controlling levers in accordance with the thicknesses of the materials at said respective needles.
5. The combination of a work support, an overhanging arm, a needle bar, two needles carried by said needle bar, a thread guide at the upper end of the needle bar for the needle threads, tension devices on the overhanging arm for the needle threads, a thread controlling lever pivoted to the overhanging arm for each needle thread, a thread guide carried by each thread controlling lever, the thread guides on the controlling levers being so disposed relative to the tension devices and the guide on the end of the needle bar whereby movements of the levers will either give or take up slack thread in the respective needle threads, a presser foot, said
- 10
15
20
25
30
35
- presser foot being divided longitudinally to form two separate yielding sections, said sections of the presser foot being so disposed as to be respectively responsive to the thickness of the material operated on by the respective needles, devices for connecting one section of the presser foot with the thread-controlling lever coöperating with the needle thread of the needle operating on the material engaged by said section of the presser foot, and devices for connecting the other section of the presser foot.

In testimony whereof I affix my signature in the presence of two witnesses.

DUDLEY S. SEYMOUR.
